CLAIM

The ornamental design for a support for computer terminals and computer keyboards, as shown and described.

DESCRIPTION

FIG. 1 is a front elevation view of the support for computer terminals and computer keyboards showing my new design;

FIG. 2 is a bottom plan view thereof;

FIG. 3 is a top plan view thereof;

FIG. 4 is a right side elevation view thereof;

FIG. 5 is a left side elevation view thereof;

FIG. 6 is a rear elevation view thereof; and,

FIG. 7 is a top perspective view thereof.

The broken lines immediately adjacent to the claim depict the bounds of the claimed design, while all other broken lines are directed to environment. The broken lines form no part of the claimed design.
